UNITED STATES PATENT OFFICE

170,640

TIRE

Walter Humphries, Erdington, Birmingham, England, assignor to Dunlop Tire and Rubber Corporation, Buffalo, N. Y., a corporation of New York

Application April 28, 1953, Serial No. 24,731
In Great Britain February 7, 1953

Term of patent 14 years

(Cl. D90—20)

To all whom it may concern:

Be it known that I, Walter Humphries, a subject of the Queen of Great Britain, have invented a new, original, and ornamental Design for a Tire, of which the following is a specification, reference being had to the accompanying drawing, forming a part hereof.

Fig. 1 is a perspective view of a tire showing my new design;

Fig. 2 is a fragmentary perspective view thereof; and

Fig. 3 is a fragmentary top plan view thereof.

I claim:

The ornamental design for a tire, as shown.
WALTER HUMPHRIES.
